CLAIM

The ornamental design for a wristwatch, as shown and described.

DESCRIPTION

FIG. 1 is a front view thereof of a wristwatch showing my new design;

FIG. 2 is a perspective view of the front and right side thereof; FIG. 3 is a right side elevational view thereof;

FIG. 4 is a rear elevational view thereof;

FIG. 5 is a left side elevational view thereof;

FIG. 6 is a bottom plan view thereof; and,

FIG. 7 is a rear elevational view of the face thereof.

The broken lines in the drawing figures show environmental structures only, and form no part of the claimed design.
